UNITED STATES PATENT OFFICE.

HERBERT H. ROOSA, OF LINCOLN, NEBRASKA.

CLAMPING DEVICE FOR SHOE-HEELS.

1,392,357.

Specification of Letters Patent.

Patented Oct. 4, 1921.

Application filed September 27, 1917. Serial No. 193,419.

To all whom it may concern:

Be it known that I, HERBERT H. ROOSA, of Lincoln, in the county of Lancaster and State of Nebraska, have invented certain new and useful Improvements in Clamping Devices for Shoe-Heels; and I do hereby declare the following to be a full, clear, and exact description of the same, reference being had to the accompanying drawings, forming a part of this specification, and to the reference-numerals marked thereon.

My invention has for its purpose to provide an improved clamping device, to be used in gluing or cementing high heels, French heels, or any wooden heels to boots, shoes, slippers or pumps.

An especial object of my improvement is to afford a clamping device so constructed that the pressure or clamping action will be distributed evenly over the entire bottom of the heel and against the heel seat, so as to avoid concentration of the clamping action at one portion of the edge of the heel, such as occurs if the ordinary type of parallel jaw clamp is employed.

A further purpose of my improvement is to provide a device readily adaptable to heels of different sizes, in such a manner that the clamp will accommodate itself to heels of different pitch, and also to afford to the operator unobstructed view of the base of the heel, and the heel seat, and ample space to beat up and mold the heel seat.

Still an additional object is to afford a portable device such that the shoe can readily be subjected to various finishing operations with the heel clamped in position, thus permitting the cement or glue to set while other work is being performed upon the shoe.

Another object of the invention is to provide a structure with a minimum number of parts, simplifying the operation and reducing the manufacturing cost, and in arranging the parts so as not to interfere with or damage the shoe upper, or crush or deface the heel while the parts are in clamped relation. To these and other ends the invention consists in certain improvements and combinations of parts all as will be hereinafter more fully described, the novel features being pointed out in the claims at the end of the specification.

In the drawings:

Figure 1 is a side elevation of a device constructed in accordance with the invention and illustrating in dotted lines a posi-

tion to which the clamp carrier can be swung away from the vertical;

Fig. 2 is a front elevation;

Fig. 3 is a bottom plan view of the top of 60 the clamp carrier with the clamping screw and guide rods removed;

Fig. 4 is a top plan view of the clamp removed;

Fig. 5 is a side elevation of a modified 65 arrangement of the invention, as designed for portable use, and showing in dotted lines the position of the clamp carrier when adjusted away from the vertical;

Fig. 6 is a front elevation;

Fig. 7 is a plan view of the last support 70 illustrated in Fig. 6, with the other parts removed, and

Fig. 8 is a front elevation, partially broken away, showing the portable clamp- 75 ing device arranged upon a last engaging pin.

Similar reference numerals in the several figures indicate the same parts.

There are various ways in which the invention may be carried out practically, and for the purpose of this application I have illustrated a preferred way of its accomplishment by way of example, and it will be understood that it is not intended to confine 85 the invention to the particular structure shown. Referring to Figs. 1 to 4, 1 designates a base which in this instance constitutes the last support and is provided with a last engaging pin 2 held in place by a set 90 screw 5, and arranged to hold a last with a shoe upper thereon, as usual in this art. Pivotally mounted upon the last support is a clamp carrier, preferably embodying guide rods 3 having inturned lower extremities 95 which engage bearings 4 in the last support 1. The guide rods 3 are connected at their upper ends by a cross head 8 which is retained in fixed relation to the guide rods by enlargements 10 upon the latter, which are 100 riveted down against the upper surface of the cross head 8.

6 designates the clamp which is provided with openings 11 to receive the guide rods 3, and is thus slidably longitudinally of the 105 carrier upon the guide rods. The clamp 6 is provided with a clamping surface 16 which is inclined with reference to a plane perpendicular to the general direction of clamping action. The inclined clamping surface 16 preferably extends from one end of the clamp to the other, and is arranged

so as to conform to the inclination of the bottom of a French heel or high heel such as used on ladies' shoes, with reference to the heel seat.

5 As the heels become larger and lower, the inclination of the bottom of the heel becomes less, or in other words, the bottom of the heel becomes more nearly parallel to the heel seat, and this is provided for in the 10 present structure by the pivoting of the clamp carrier which can be swung around the last support, as indicated by dotted lines in Fig. 1. As the clamp is thus moved laterally, its inclined clamping surface 11 becomes more nearly horizontal, thus conforming to the bottom of a heel which is larger or less inclined than the extreme French heel.

The clamping surface 16 terminates in a 20 shoulder 17, which engages the rear edge of the heel and assists in positioning the parts. When in clamped position, the surface 16 engages over substantially the entire bottom of the heel, and the pressure is thus distributed 25 throughout the heel. This affords an even engagement between the heel and its seat, thus more securely attaching the parts, and it also obviates the danger of creasing or defacing the covering of the heel or otherwise damaging the heel, as when the pressure is applied at its one edge only, causing greater compression through one portion of the heel than another.

The clamp is actuated by a clamping 35 screw 7, which is threaded in an opening 12 of the cross head 8, and is provided with an operating handle 9. The operation will be readily understood and consists in positioning a last, with a shoe upper and sole thereon, upon the last engaging pin 2, and after the heel is supplied with glue or cement and properly positioned upon the shoe seat, the clamp 6 is brought down upon the bottom of the heel. The clamp carrier is adjusted 40 about its pivotal axis until the clamping surface correctly conforms to the inclination of the bottom of the heel, and the clamping screw 7 is then tightened.

In some cases it is quite desirable to perform 50 other work on the shoe with the heel clamped thereon, and for this purpose I provide the mechanism shown in Figs. 5 to 8 inclusive. In this form, instead of using a large base, such as shown in Figs. 1 and 2 for the last support, I employ a last support 13 upon which the guide rods 3' of the clamp carrier are pivoted in sockets 14. The last support 13 is provided with a central opening 15 to temporarily receive a last pin 2, while the heel is being clamped to the shoe. The operation and remaining parts are the same as already described, and after the heel is clamped, the entire structure can be removed 60 from the last pin 2. This arrangement affords a light, portable device that

can be readily carried to permit other finishing operations upon the shoe while the glue under the heel is hardening.

The last support 13 is cut away slightly upon its upper surface at opposite sides of 70 the center part, as indicated at 18. The purpose of this is to provide a slight clearance between the last and the end portions of the last support, so as to prevent tightly engaging any part of the shoe upper, and pinching or damaging it. The space afforded between the guide rods 3' is sufficient to permit the shoe upper to be received without crushing, and makes it possible to gain access readily to the shoe for other finishing 80 operations while the clamp remains applied.

I claim as my invention:

1. In a clamping device for shoe heels, the combination with a last support, of a clamp carrier pivotally mounted with reference 85 to the last support to swing about the same and including oppositely arranged guide rods, and a clamp having openings receiving said guide rods and movable thereon toward and from the last support and having a clamping surface inclined with reference to a plane perpendicular to the general direction of clamping action so as to conform to the heel pitch and terminating in a 90 shoulder positioned for engagement with the rear edge of a heel.

2. In a clamping device for shoe heels, the combination with a last support having an opening to receive a last engaging pin, of a clamp carrier pivotally mounted with 100 reference to the last support to swing about the same, and a clamp slideable longitudinally of the carrier toward and from the last support and having a clamping surface inclined with reference to a plane perpendicular to the general direction of clamping action so as to conform to the heel pitch and terminating in a shoulder positioned for engagement with the rear edge of a heel.

3. In a clamping device for shoe heels, 110 the combination with a last support having an opening to receive a last engaging pin, of a clamp carrier pivotally mounted with reference to the last support to swing about the same and including oppositely arranged guide rods, and a clamp having openings receiving said guide rods and movable thereon toward and from the last support and having a clamping surface inclined with reference to a plane perpendicular to the 115 general direction of clamping action so as to conform to the heel pitch and terminating in a shoulder positioned for engagement with the rear edge of a heel.

4. In a clamping device for shoe heels, 125 the combination with a last support, of parallel spaced guide rods pivotally mounted on said last support to swing about the latter, a clamp bar having perforations therein through which said rods pass, a clamping 130

surface on said bar inclined with respect to said rods and terminating in a shoulder for engaging with the rear edge of a shoe heel, and means for sliding said clamp bar on 5 said rods toward and from said support.

5. In a clamping device for shoe heels, the combination with a last support, of parallel spaced guide rods pivotally mounted on said last support to swing about the latter, a clamp bar having perforations therein through which said rods pass, a clamping surface on said bar inclined with respect to said rods and terminating in a shoulder for engaging with the rear edge of a shoe heel, 10 a last engaging pin on said support and projecting toward said bar, and means for sliding said bar on said rods toward and from said support.

6. In a clamping device for shoe heels, the combination with a last support, of a clamp carrier pivotally mounted with reference to said last support to swing about the same including spaced guide rods provided with straight parallel bearing portions, a clamp 15 having openings therein forming bearings 20 encircling said rod bearing portions and

adapted to rigidly support said clamp against angular movement relative to a plane perpendicular to the general direction of clamping action, and means for sliding said 30 clamp on said rod portions toward and from the last support.

7. In a clamping device for shoe heels, the combination with a last support, of a clamp carrier pivotally mounted with reference to 35 said last support to swing about the same including spaced guide rods provided with straight parallel bearing portions, a clamp having openings therein forming bearings 40 encircling said rod bearing portions and adapted to rigidly support said clamp against angular movement relative to a plane perpendicular to the general direction of clamping action, a clamping surface 45 on said clamp inclined with reference to said plane to conform to the heel pitch and terminating in a shoulder positioned for engagement with the rear edge of a heel, and means for sliding said clamp on said rod portions toward and from the last support.

HERBERT H. ROOSA.
